UNITED STATES PATENT OFFICE.

HEINRICH BOCKISCH, OF POUGHKEEPSIE, NEW YORK, ASSIGNOR, BY MESNE ASSIGNMENTS, TO WELTE-MIGNON CORPORATION, OF NEW YORK, N. Y., A CORPORATION OF NEW YORK.

AUTOMATIC MUSICAL INSTRUMENT.

Application filed November 20, 1919. Serial No. 339,261.

To all whom it may concern:

Be it known that I, HEINRICH BOCKISCH, a citizen of Czecho-Slovakia, residing at Poughkeepsie, in the county of Dutchess and State of New York, have invented certain new and useful Improvements in Automatic Musical Instruments, of which the following is a specification.

This invention has relation to record-controlled musical instruments of the kind set forth in Patents Numbers 1,197,573; 1,197,574 and 1,197,575, issued September 5, 1916, to Heinrich Bockisch, Assignor to M. Welte & Sons, of New York, N. Y., a corporation of New York, and also set forth in my companion application "Case A" for patent Serial Number 339,260, filed of even date herewith, and application "Case C" to be filed later.

In other words, this invention is a further particular embodiment of a mechanism wherein there is a plurality of series, or scales, of tone emitting elements, as organ pipes for example, one of said series being for tones having a different quality than the other, as pedal and manual for instance, and record controlled means for selectively causing the operation of any one or more of the tone emitting elements of either series alone, or of any one or more of the elements of one series in combination with any one or more of the elements of the other series.

The embodiment illustrated in the accompanying drawings comprises many parts and correlations of parts which are generically similar to what has been shown, described and claimed in my patents hereinbefore named. Moreover, it comprises parts and correlations of parts which are specifically identical with parts and correlations of parts set forth and claimed in my said companion application of even date herewith.

The new features upon which the present application is based are exemplified by the mechanism herein illustrated for carrying the movable members embodied in the tone connections and for operating said members from the primary operating pneumatics. In

this invention the movable members referred to are carried by circuit closing devices and each series of said circuit closing devices and members (that is to say, the series of circuit closing devices and members for one scale of tone emitting elements, and similarly, the series of levers and members for the other scale of tone emitting elements) is provided with an operating member common thereto. These operating members act through the respective series of levers to thereby move said members into engagement with corresponding elements of the tone connections, the said corresponding elements in this application, as in my before mentioned companion application, being, preferably, contact wires arranged in pairs and forming parts of electrical tone circuits and the said movable members being, in such case, electrical circuit closing elements for bridging the spaces between the pairs of contact wires, respectively. The movable operating members for the series of levers, respectively, are provided with elements of a yieldable nature to engage the levers, respectively, and these form one of the new features in this embodiment of the invention. Another of the new features of the present invention has relation to the primary operating pneumatics and especially the connection between the same and the operating members hereinbefore referred to; and a further new feature in the present embodiment of the invention has relation to the valvular means by which the relative pneumatic forces which control the primary operating pneumatics are controlled from the respective record controlled primary control valves.

Having thus in a general way set forth the relationship of this embodiment to other embodiments which have been made the subject of generic claims in my patents and application for patent hereinbefore referred to, I will in following portions of this specification set forth this embodiment somewhat minutely both as regards the old and the new features thereof, without intending thereby to restrict the invention to the particular details set forth, as changes in the details

may be made without departing from the spirit of the invention as defined by the appended claims.

In the accompanying drawings, wherein like characters of reference denote corresponding parts in the several views:

Figure 1 is a diagrammatic view of a system which exemplifies the preferred embodiment of the present improvements;

10 Figure 2 is a perspective view of the part of the switching mechanism involving novel features, arbitrarily assumed, as shown by the reference characters thereon, to be included in the pedal scale, but as the manual 15 scale embodies a part of identically the same construction, it is apparent that this view similarly illustrates the corresponding parts in said manual scale;

Figure 3 is an end view of the same parts 20 of the switching mechanism, showing the position thereof when the circuits in the pedal portions of the mechanism are interrupted, i. e., when bridging members g are out of contact with contact wires c ;

25 Figure 4 is a vertical section through the same parts, showing the positions of the elements when circuits in the pedal scale are completed;

Figure 5 is a plan view of the switching 30 mechanism arbitrarily assumed to be for the pedal scale but equally illustrative of the manual scale;

35 Figures 6, 7, and 8 are views of different portions of the note sheet preferably employed as the record to control the operation of the instrument.

40 D is a tracker board having tone ducts 12 common to a plurality of scales, as a manual scale and pedal scale, for example, and also having control ducts 1 and 2.

45 14 designates a primary tone valve whose stem is connected to a membrane 17 mounted between a chamber 13 and a suction conduit 13^a, the valve itself being mounted in a chamber, 14^a, having a suction port 20 and an atmospheric port 19. In practice there is one of these valves, membranes, chamber 13, and chamber 14^a for each note common to both scales, and additional valves, membranes and chambers for each note which is 50 to be played in the manual scale only, for example. As this invention is concerned only with those notes which are common to a plurality of scales, the description will 55 be confined to the parts by which the sounding of the notes in either scale alone, or in both scales together, in any combination called for by the musical composition, is permitted, notwithstanding the use of primary tone valves and tone ducts common to both scales. It will be understood that the several chambers 13 and 14^a are, in practice 60 preferably embodied in a chest (a section of which is shown at K) called primary tone chest, and that the conduit 13^a, also in

said chest, may be common to the several valves 14 and membranes 17 and suitably connected with a means for attenuating the air therein. The ducts 12 are connected to the chambers 13, respectively, and serve to 70 admit atmospheric air to the membranes 17 to thereby move the primary tone valves 14 to close the atmospheric ducts 19 and open the suction ducts 20. Each section of the chest K also has a pneumatic g^3 provided with primary tone contacts g^2 , respectively, for closing tone circuits herein- 75 after fully set forth.

F and H designate secondary operating pneumatics, having suitable connections, 80 such as indicated at F' and H', for example, with the stems c^2 of valves (not shown) in the manual and pedal wind chests as in my patents and applications for patent hereinbefore referred to. In practice, 85 there is one pneumatic F for each valve in the manual wind chest section and one pneumatic H for each valve in the pedal wind chest section.

Each pneumatic F is connected to a chamber 90 63. These chambers 63 are, in practice, preferably formed in a secondary tone chest, a section of which is shown at I in Fig. 1. Similarly, each pneumatic H is connected to a chamber 63 and these several 95 chambers 63 are preferably formed in a secondary tone chest, a section of which is shown at I' in Fig. 1.

Each chamber 63 is provided with a secondary tone valve 70, and is formed with 100 a suction port 64 and an atmospheric port 65. The valves 70 are severally moved to close the respective atmospheric ports 65 and open the respective suction ports 64 and thereby collapse the corresponding pneumatic F or H by admitting air at atmospheric pressure to chambers 66 having membranes 67 connected to the valves 70. This air is admitted to said chambers 66 through ducts 69 and these ducts are opened and 110 closed by valves 68 carried by the armatures f' , h' of electro-magnets f and h which are included in the tone circuits hereinafter fully set forth.

The control ducts 1 and 2 hereinbefore 115 referred to respectively lead to chambers 3 and 3^a formed in primary control members J and J'. The member J also has a suction chamber 4, a valve chamber 5, a suction port 6, an atmospheric port 7, a valve 8 in the 120 chamber 5 to control said ports, a membrane 9, mounted between the chambers 3 and 4 and connected to the stem of the valve 8, and a pneumatic b^6 having connection with the valve chamber 5, through a port 10, and provided with a contact member b^5 . This member J, in the herein illustrated arrangement of the parts acts, through intermediate mechanism hereinafter described, to close 125 the circuits through the magnets h , to there- 130

by collapse the pneumatics H. In short, in the herein exemplified arrangement, the opening of control duct 1 introduces pedal notes, as in my patents and application for 5 patents hereinbefore referred to. The member J' is or may embody the same construction as member J: 3 being the chamber connected to the duct 2; 4^a being its suction chamber; 5^a its valve chamber; 6^a and 7^a 10 its suction and atmospheric ports, respectively; 8^a its valve; 9^a its membrane; and a⁶ its pneumatic, having connection with chamber 5^a through port 10^a and provided with a contact member a⁵.

15 The contact member b⁵ closes a "pedal control circuit", hereinafter described, the effect of which is to complete otherwise interrupted tone circuits which control the playing of pedal notes, whereby pedal notes 20 are sounded when duct 1 is opened. The arrangement is such that when any tone duct 12 is opened and both control ducts 1, 2 are closed, the corresponding notes are sounded in the manual scale alone, and when 25 control duct 1 is open immediately prior to any tone duct 12, the corresponding notes are sounded in both the manual and pedal scales. The contact member a⁵ closes a "manual control circuit" hereinafter described, which results, as hereinafter explained, in the interruption of the tone circuits to the manual scale, when control duct 30 2 is opened, to thereby exclude manual notes and, hence, duct 2 is opened along with control duct 1 to cause the sounding of notes in the 35 pedal scale only.

As thus far described the parts are identical in structure with the corresponding parts in my application of even date herein 40 with. The present embodiment, moreover, as already stated is generically similar in many respects to the particular embodiment shown in my aforesaid application for patent, but differs therefrom in details which 45 will now be described.

The switching mechanism L for the pedal scale and the corresponding switching mechanism M for the manual scale are of substantially similar construction, as follows: 50 The manual mechanism M comprises a series of secondary tone circuit closing elements e—one for each manual note—for opening and closing parallel electric circuits which form parts of tone circuits including 55 the magnets f: and similarly, the pedal mechanism L comprises a series of secondary tone circuit closing elements g for opening and closing parallel electric circuits which form parts of tone circuits including 60 the magnets h. Each of the parallel circuits of the pedal mechanism has a series of pairs of contact wires c, c', (as indicated in Fig. 1 and shown more clearly in Figs. 2 and 5), to be bridged by the respective circuit 65 closing elements g, and each of the parallel

circuits of the manual mechanism has a similar series of pairs of contact wires d, d', (indicated in Fig. 1), to be bridged by the respective circuit closing elements e. The circuits are hereinafter fully stated. 70 As thus far described the switching mechanism is generically similar to the switching mechanism of my beforementioned application for patent. However, in this particular embodiment, the circuit closing elements e 75 and g are carried by circuit closing devices 61 and 58, respectively, pivoted at 61^a and 58^a, and they are moved into operative relation with the before-mentioned contact wires by operating members P and Q, there 80 being one operating member P for the entire series of levers 61 of the manual scale and a separate operating member Q for the entire series of levers 58 of the pedal scale. The opposite ends of each operating member 85 P, Q are connected to rock arms P', Q'. The rock arms P' of the manual mechanism derive motion from a suitable number of primary operating pneumatic elements E whose movable boards are connected by 90 links p' with cranks p² projecting from a rock shaft p³ having cams p⁴ to engage the adjacent ends of said rock-arms; and, similarly, the rock arms Q' of the pedal mechanism derive motion from a suitable number 95 of primary operating pneumatics G whose movable boards are connected by links q' with cranks q² projecting from a rock shaft q³ having cams q⁴ to engage the adjacent ends of said rock arms. It will thus be seen 100 that the circuit closing elements e, g are thus, generically, pneumatically operated by means which include primary operating pneumatics but that the mechanism set forth between the primary operating pneumatics 105 and the circuit closing elements does not require a separate operating pneumatic for each circuit closing element.

The primary operating pneumatic elements E for the manual tones or effects are 110 normally collapsed and hence the circuit closing elements e are normally in engagement with the contact wires d, d'. The primary operating pneumatic elements G for the pedal tones or effects, on the other hand, 115 are normally expanded and consequently the circuit closing elements g are normally out of engagement with the contact wires c, c'. This relation of the parts, which has arbitrarily been called the "normal" one because 120 it is the one which most frequently exists in the operation of the mechanism, results in the sounding of the manual tones or effects alone. If pedal tones or effects are to be introduced with manual tones or effects, 125 then the operating pneumatic elements G are collapsed to move circuit closing elements g into engagement with contact wires c, c', the pneumatic elements E remaining in their collapsed condition: and if pedal 130

tones or effects alone are to be sounded, pneumatics E are expanded, thereby rocking shafts p^3 and removing the pressure of cams p^4 from the rock arms P' and allowing said arms to turn pivotally and permit the member P to recede from the circuit closing devices 61 and the latter (except those which are restrained against such movement as hereinafter set forth) to move 10 by gravity, for example away from the contact wires d, d' .

The interior of the primary operating pneumatic element E for the manual is connected by a duct 24 with a chamber 26 having a suction port 26^a and an atmospheric port 26^b. A secondary valve 25 is mounted in this chamber and is arranged to open the suction port and close the atmospheric port, or to close the suction port and open the atmospheric port. The first named position is its normal one, and hence pneumatic E is normally collapsed through duct 24, chamber 26, port 26^a, and suction chamber 26^b. To hold the valve 25 in this position (and to 25 provide for its being moved therefrom to close suction port 26^a and open atmospheric port 26^b when pneumatic E is to be expanded), I provide a membrane 27 which is arranged between two chambers 27^a and 27^b, one of 30 which chambers, as 27^b, is always under suction, being connected to suction chamber 26^a by channel 26^d, while the other chamber, 27^a, is normally under atmospheric pressure which is exerted against the membrane 27 35 in a direction to hold the valve 25 away from the suction port 26^a and over the atmospheric port 26^b. The chamber 27^a is connected by a duct 27^c with a chamber 28 having an atmospheric port 28^a and a suction port 28^b. In this chamber 28 there is a sub-primary control valve 29 arranged to close the suction port 28^b and open the atmospheric port 28^a, and vice versa. The former is its normal position and hence chamber 40 27^a is normally under atmospheric pressure, as set forth. The valve 29 has its stem 29^a connected to a membrane 30 which is arranged between a suction chamber 31 and a chamber 32, the latter chamber having an atmospheric duct 33 which is controlled by a valve 34 on the armature 35 of an electro-magnet 37.

It will be apparent that when the magnet 37 is not energized the duct 33 will be closed 55 by the valve 34 and that when said magnet is energized it will attract its armature, thereby opening the atmospheric duct 33 and admitting air at atmospheric pressure to the chamber 32, whereupon valve 29 will be moved and will close the atmospheric port 28^a and open suction port 28^b. Chamber 27^a will now be under suction and as chamber 27^b is always under suction, it follows that the pneumatic forces on opposite sides of the 60 membrane 27 will counterbalance each other,

and valve 25 will fall and open atmospheric port 26^b and close suction port 26^a, whereupon the pressure within pneumatic element E will equal the external pressure exerted on the movable board thereof, thereby permitting the spring E' of said pneumatic element to expand it for the purpose already explained. 70

Magnet 37 is energized for the purpose set forth from one of the primary control 75 ducts, as duct 2 for example, through the primary control member J', whose valve 8^a is normally in such position that the pneumatic a^6 is expanded, but which valve when its control duct is opened is moved to close 80 atmospheric port 7^a and open suction port 6^a, thus collapsing pneumatic a^6 and moving its contact a^5 into bridging relation with contact wires x^2, x^3 , thereby closing an electric circuit, through the magnet 37. This 85 circuit, which is called "manual control circuit" may be traced diagrammatically as follows:

From a suitable source of electrical potential, indicated at P, by wire x and branch x' 90 to contact wire x^2 , thence through contact a^5 and contact wire x^3 and wire x^4 to the magnet 37, and from said magnet by wires x^5, x^6 , and x^7 to a terminal x^8 in a negative bus bar X and back to the source P by the 95 wire x^9 .

Substantially similar connections are, or may be, employed to expand and contract the primary operating pneumatic element G for the pedal scale, arranged, however, to 100 keep said pneumatic element in normally expanded condition. The magnet for the pedal member of the switch, is marked 49: the remaining elements for said member are designated as follows: 38, secondary control 105 valve; 39, secondary control-valve chamber; 39^a, suction port to secondary valve chamber; 39^b, atmospheric port to secondary control valve chamber; 40, membrane connected to the stem 38^a of the secondary control- 110 valve; 41^a and 41^b chambers on opposite sides of said membrane, chamber 41^b being constantly in communication with the atmosphere; 41^c a duct extending from chamber 41^a and through which said chamber is 115 normally in communication with the atmosphere; 42, chamber for subprimary control valve; 42^a and 42^b, atmospheric and suction ports respectively to said chamber; 43, sub-primary control-valve; 43^a its stem; 44, 120 membrane connected to said stem; 45, suction chamber on one side of the membrane; 46, chamber on the other side of the membrane; 47, atmospheric duct leading to the latter chamber; 48, valve for opening and 125 closing said duct; and 49^a, armature to which said valve is connected.

It will be apparent that when magnet 49 is energized, valve 48 will be raised, thereby opening duct 47 to the atmosphere, thus 130

causing valve 43 to open suction port 42^b and close atmospheric port 42^a. The air in chamber 41^a will now be attenuated from chamber 45, (through chamber 45, port 42^b, chamber 42 and duct 41^c) and, as the pressure of the air in chamber 41^b remains atmospheric, it will follow that the secondary control-valve 38 will be raised and will open suction port 39^a and close atmospheric port 39^b. Pneumatic elements G will now be under suction and will collapse and rock the shaft g³ resulting, through the elements already set forth, in the raising of the entire series of circuit closing element g (except those which are restrained against such movement, as hereinafter set forth,) into engagement with the respective pairs of contact wires c, c.

The magnet 49 is energized from the control duct 1, through the primary control member J, whose valve 8 is normally in such position that the pneumatic b⁶ is expanded, but which valve, when duct 1 is opened, is moved to close atmospheric port 7 and open suction portion 6, thus collapsing pneumatic b⁶ and moving contact b⁵ into bridging relation with contact wires b and b⁸, thereby closing a control-circuit, hereinafter set forth, which circuit includes the magnet 49. This circuit, called "pedal control circuit" may be traced diagrammatically as follows:—

From the source P by wire x and branch x¹⁰ to contact wire b, and through the contact b⁵ and contact wire b⁸ and wire x¹¹ to the magnet 49, and from said magnet, by way of wires x⁶ and x⁷ to the negative bus bar X and thence back, through wire x⁹, to the source P.

The operation of energizing magnet 49 to adjust the circuit closing elements g into bridging engagement with contact wires c' to include pedal tones or effects with manual tones or effects occurs immediately prior to the opening of the ducts 12 for the notes to be affected. Moreover, the energizing of these magnets 37 and 49 ceases at the moment the duct or ducts 12 for the tones to be affected, are opened. The energizing of magnet 49 or magnets 37 and 49 accordingly are preparatory functions tending to result in the collapsing of the operating pneumatic elements G and the moving of all circuit closing elements g into bridging engagement with contact wires c, c', when magnet 49 is energized and the moving of all of said contacts out of engagement with said wires when the circuit to this magnet is broken, and, similarly, tending to result in the expanding of the operating pneumatic elements E and the moving of all circuit closing elements e out of bridging engagement with contact wires d, d', when magnet 37 is energized and the moving of all said contacts into engagement

with said wires when the circuit to the latter magnet is broken.

This tendency, however, as will be readily seen by those who are familiar with my inventions relating to the automatic control of mechanisms of this nature, must be resisted or rendered non-effective with relation to the contacts corresponding to tone ducts which are open at the moment either control duct is open, to thereby assure the maintenance of the tones for the full length of time their respective tone ducts are open, uninterrupted by the opening of either control duct to affect succeeding tones.

For this reason, in this particular embodiment of the invention, I employ the hereinbefore described series of independently pivoted circuit closing devices 61 and 58 and provide individually yieldable supporting elements or connections between the operating members P and Q and the circuit closing devices and further provide locking elements, as pneumatics 75 and 77, for example, which are controlled from the tone circuits, hereinafter set forth, and hence are maintained in locking engagement with the respective circuit closing devices 58, 61, from the moment the corresponding tone ducts are opened to the moment they are closed.

The preferred form of yieldable connections employed between each circuit closing devices 58 and common operating member Q for the series of devices 58 and between each circuit closing device 61 and the operating member P common to the series of devices 61 is shown best in Figures 3 and 4, it being understood that while these figures represent characters which indicate them as illustrating part of the pedal scale mechanism, they nevertheless also illustrate corresponding parts of the manual scale, as the structure of these two parts, i. e. of the pedal and manual scales, is or may be identical. Upon reference to these figures it will be seen that the operating member P (or Q) has a chamber 50 which receives the stem 51 of a holding element having a head 52 to engage the underside of the corresponding contact lever 58 (or 61). The chamber is provided with a spring 52' which encircles the stem 51 and said stem is provided with a collar 53 forming an abutment against which the spring presses. Each circuit closing device 58, 61 is preferably provided with a retracting spring 54.

The locking mechanism here shown is substantially identical with that shown and described in my beforementioned application for patent, of even date herewith. The locking pneumatics 75 of the pedal section have projections 76 to engage projections 76^a from the contact levers 58, respectively, and, similarly, the locking pneumatics 77 of the

manual section have projections 78 to engage projections 78^a from the levers 61, respectively.

For each pair of locking pneumatics 75, 77—that is to say, for each pneumatic 75 of the pedal and the pneumatic 77 for the same note in the manual—there is a valve 84 which is mounted in a chamber having a suction port 82 and an atmospheric port 82^a.
10 Each chamber 83 is connected by ducts 79 and 80 with the corresponding pair of locking pneumatics 75, 77, respectively. The valves 84 are moved individually to close the corresponding atmospheric ports 82^a and 15 open the corresponding suction ports 82 by the admission of air at atmospheric pressure to respective chambers 87 having membranes 88 connected to the valves. This air enters the chambers through ducts 90, respectively, 20 and these ducts are controlled by valves 92 carried by the armatures 91^a of electro-magnets 91, the circuits of which are opened and closed from the respective primary tone valves 14. Hence, the magnets 91 are in tone 25 circuits so that the respective pairs of locking pneumatics 75, 77, are controlled by the tone circuits, as in my application hereinbefore referred to.

Accordingly, it will be seen that whenever 30 a tone duct 12 is opened, the corresponding locking pneumatics 75 and 77 are deflated and their projections 76, 78 are moved into engagement with the projections 76^a, 78^a of the corresponding circuit closing devices 58, 35 61, thus holding said levers in the position occupied by them when the corresponding tone duct 12 was first opened and maintaining them in that position until said duct is closed. For example, when the organ is first 40 started, and assuming that the first tone or tones are manual tones only, and hence all circuit closing elements *e* are in engagement with their respective pairs of contact wires *d*, *d'* and all circuit closing elements *g* are 45 out of engagement with their respective pairs of contact wires *c*, *c'*, (neither control duct being open at this time) the opening of any tone duct 12 will complete the circuit 50 through the corresponding magnet 91, whereupon the corresponding locking pneumatics 77 and 75 will immediately collapse. The projection 78 from the collapsed pneumatic 77 will thereby move beneath the projection 78^a of the corresponding circuit closing devices 61 and remain in that position 55 until the tone duct is again closed: and, at the same time, the corresponding pneumatic 75 will collapse and its projection 76 will move over the projection 76^a of the corresponding circuit closing device 58 and will 60 remain there until the tone duct is again closed. Hence, circuit closing element *e* corresponding to the open tone duct 12 cannot move out of engagement with contact wires 65 *d*, *d'*, nor can the circuit closing element *g*

corresponding to the same tone duct move into engagement with contact wires *c*, *c'*, until said tone duct is again closed, even if control duct 1, or both control ducts 1 and 2, meanwhile are opened. Accordingly manual 70 tones corresponding to tone ducts 12 which were opened before control duct 1, or control ducts 1 and 2, are opened, continue uninterrupted by the opening of said control ducts until the tone ducts have been closed, the 75 closing of said tone ducts breaking the circuits to the corresponding magnets 91 and changing the tension of the air in pneumatics 75 and 77 to atmospheric, thus causing said pneumatics to expand and release 80 the corresponding devices 58 and 61. The control ducts are opened in advance of the opening of the ducts 12 corresponding to tones which they are to affect and are closed 85 shortly after said tone ducts are opened. 85

To introduce pedal tones with corresponding manual tones, duct 1 alone is opened, the manual mechanism being normally operative as already stated, and if pedal tones are 90 to be played without corresponding manual tones, then duct 2 is opened to exclude the manual tones and duct 1 is opened at the same time to include pedal tones.

The opening of contact duct 1 will result in the energizing of magnet 49 and this in 95 turn will cause the operating pneumatics *G* to collapse, thus raising the operating member *Q* and forcing all circuit closing devices 58 (except those which are held by collapsed pneumatics 75, i. e., the locking pneumatics 100 75 corresponding to open tone ducts) toward the wires *c*, *c'*.

The opening of control duct 2 results in the energizing of magnet 37 and this in turn will cause the operating pneumatic elements *E* to expand, thereby releasing operating member *P*, which is thus allowed to recede from the wires *d*, *d'*, all the devices 105 61 following this movement of said member, except those which are held by collapsed 110 pneumatics 77.

It will be noted that the springs 52' permit movement of the operating members *Q* and *P* relatively to the devices 58 and 61 and are placed under tension if their respective levers are held against movement toward the contact wires *c*, *c'* or *d*, *d'*, with the operating members, so as to force their several levers toward said wires, as soon as the levers have been released. It will also 115 be noted that the springs 54 are placed under tension when their respective devices 58 or 61 are held against movement away from the wires *c*, *c'*, or *d*, *d'*, with the members *P* or *Q* and become effective to retract said 120 levers as soon as the latter have been released.

As already stated, the tone circuits are completed when the tone ducts 12 are opened, respectively, the opening of said ducts caus- 130

ing the corresponding pneumatics g^3 to collapse and move their contact elements g^2 into bridging engagement with the space between respective pairs of contact wires g' and g^4 . These circuits may be traced as follows:

From the positive pole of the source P by wire x and branch x^{14} to contact wire g' and through the bridging contact g^2 , contact wire g^4 and wire x^{15} to a terminal g^6 and through the corresponding magnet 91 to the corresponding terminal x^8 on the negative bus bar X and back to the source P. This energizes the corresponding magnet 91 and deflates the locking pneumatics 77 and 75. The magnets f are included in parallel circuits which may be interrupted by movement of the contacts e away from the contact wires d d' and the magnets h similarly are in parallel circuits which may be interrupted by movement of the contacts g away from the contact wires c , c' . As already stated these circuits form parts of the tone circuits. If neither of the control ducts has just been opened the tone will be sounded in the manual alone because the operating pneumatic elements E are collapsed and the circuit closing elements e are in engagement with the contact wires d d' . The several contact wires d are connected by wires x^{16} to the respective terminals g^6 and the several contact wires d' are connected by wires x^{17} to one side of respective magnets f , the other sides of which 35 magnets are connected with the negative bus bar X. On the diagrammatic view the circuit would be traced as follows, when neither control duct 1 or 2 is opened, namely: from the positive pole of the source P, by wire x and branch x^{14} to contact wire g' ; by bridge contact g^2 , contact wire g^4 ; and wire x^{15} to terminal g^6 ; by wire x^{16} to contact wire d ; through circuit closing element e and contact wire d' and by wire x^{17} to 40 one side of the magnet f ; through said magnet and by wires x^{18} , x^{19} and x^7 to terminal x^8 in the negative bus bar X and back to the source by way of wire x^9 . If control duct 1 has been opened, thereby energizing 45 magnet 49 and resulting in the collapsing of pneumatic element G and the bringing of circuit closing elements g into engagement with contact wires e , magnet h in addition to magnet f corresponding to open tone duct 12 will be energized. The circuit through magnet f will of course be the same as that already described while the circuit through magnet h may be traced on the diagrammatic view as follows: from the 50 source to terminal g^6 by the way already described; thence by wire x^{20} to contact wire c and through circuit closing element g and contact wire c' and wire x^{21} to one side of corresponding magnet h ; through 55 said magnet and by wire x^{22} and wire x^7

to the negative bus bar X and back to the source.

If pedal tones only are to be sounded, control ducts 1 and 2 will have been opened immediately prior to the opening of the duct 12 for the tone to be sounded in manual alone. Hence, when duct 12 is opened the portion of the circuit to the corresponding magnet f , between terminal g^6 and the negative bus bar X is interrupted as the corresponding contact has been withdrawn from its engagement with the contact wires d , d' .

It is believed that the invention will be fully comprehended from the foregoing description and that it will be seen that I have provided a very simple and practicable switching mechanism by which, in short, the tones sounded may be manual tones alone, pedal tones alone, or both manual and pedal tones together, in any of the infinite variety of combinations of such tones necessary to the proper rendition of musical composition, under control of a properly prepared record having tone apertures common to both the manual and pedal scales with special apertures for controlling the switching mechanism. Such a record, is shown in my patents and applications for patent hereinbefore referred to and is also shown in Figs. 6, 7 and 8 of the drawings hereof. It is marked N: its tone apertures are marked n and its control apertures are marked n' and n^2 . It need not be further described.

I would have it understood that the construction shown and described is exemplary only and that many changes may be made in details without affecting its spirit or departing from the scope of the claims. In many generic respects this invention is like that of my application before referred to, and in those respects wherein the two are common the generic claims are embodied in the other application.

Having thus described the invention what I believe to be new and desire to secure by Letters Patent, is:—

1. A record-controlled musical instrument of the kind set forth, comprising tone-connections, including a set of members for each scale of tone-emitting elements, said members being movable to render the connections operative or inoperative, record-controlled means common to said sets to cause the sounding of tones through those connections which are operative at the time said means come into operation, respectively, a record-controlled means for each set of movable members, tending to move said sets, into or out of operative relation with corresponding members of the connections, the latter record-controlled means including operating members common to the respective sets of movable members, each of said movable members having a yieldable connection with

- its operating member, and record-controlled means operated coincidently with the first mentioned record-controlled means for resisting the tendency of the operating members to move those movable members which correspond to any first-mentioned record-controlled means which is in operation at the time the operating members, respectively, are moved.
- 10 2. A record-controlled musical instrument of the kind set forth, comprising tone connections having a set of secondary circuit making and breaking members for each scale of tone-emitting elements and record-controlled primary circuit making and breaking elements common to both scales, a record-controlled operating means for each set of secondary circuit making and breaking elements, each including an operating member common to its set of circuit making and breaking members, a yieldable connection between each secondary circuit making and breaking member and its operating member, locking means for the respective secondary circuit making and breaking members, and connections through which the locking means are controlled by the primarily circuit making and breaking members.
- 15 3. A record controlled musical instrument of the kind set forth including a set of circuit making and breaking members for each scale of tone-emitting elements, a record-controlled means for controlling both sets of circuit making and breaking members, including common operating members for the respective sets, a yieldable connection between each circuit making and breaking member and its operating member, a set of locking members for each set of circuit making and breaking members, and record-controlled means including elements common to the two sets of circuit making and breaking members and the two sets of locking members and connections between said elements and members, for controlling the circuits which include the former and co-incidently operating the corresponding locking members.
- 20 4. A record-controlled musical instrument of the kind set forth, comprising tone-connections including a set of members for each scale of tone-emitting elements, said members being movable to render the connections operative or inoperative, record-controlled means common to said sets to cause the sounding of tones through those connections which are operative at the time said means comes into operation, respectively, a record-controlled means for each set of movable members, tending to move said sets into or out of operative relation with corresponding members of the connections, the latter record-controlled means including operating members common to the re-
- 25 5. In a record-controlled musical instrument, having a plurality of scales of tone-emitting elements: a series of tone-ducts common to said scales, a set of tone-connections for each scale, each connection having a member movable to make the connection operative or inoperative, an operating member for each set of movable members, each of said movable members having a yieldable connection with its operating member, control ducts, connections between the control ducts and the operating members, respectively, locking elements for the movable members, respectively, and means under control of the tone-ducts for moving the locking elements into holding relation with said movable members.
- 30 6. In a record-controlled musical instrument, having a plurality of scales of tone-emitting elements: a series of tone-ducts common to said scales, control ducts for the respective scales, tone circuits having movable circuit making and breaking members, an operating member common to the circuit making and breaking members of one scale, a second operating member common to the circuit-making and breaking members of the other scale, each circuit making and breaking member having a yieldable connection with its operating member, connections between the tone ducts and operating members, respectively, locking elements for the circuit making and breaking members, respectively, and means under control of the tone ducts for moving the locking elements into holding relation with the circuit making and breaking members.
- 35 7. In a record-controlled musical instrument, having a plurality of scales of tone-emitting elements: a series of tone-ducts common to said scales, tone circuits having primary circuit-making and breaking members controlled by the tone-ducts, respectively, and also having a set of secondary

- circuit making and breaking members for each scale of tone-emitting elements, connections between the control ducts and the sets of secondary circuit making and breaking members, respectively, including an operating member for each of said sets, each secondary circuit making and breaking member having a yieldable connection with its operating member, a locking element for 5 each secondary circuit making and breaking member, and means under control of the tone ducts for operating the locking elements.
8. In a record-controlled musical instrument, having a plurality of scales of tone-emitting elements: a series of tone-ducts common to said plurality of scales and mechanism to bring any one or more of the tone-emitting elements of either scale alone, 10 or any one or more corresponding or non-corresponding elements of both scales together, into communication with their tone-ducts, the said mechanism including connections to the tone-emitting elements each having a set of members movable to make the connections to the respective elements operative or inoperative, a common operating member for each set of movable members, each movable member having a yieldable 15 connection with its operating member, pneumatics, connections between the pneumatics and the operating members for operating the latter from said pneumatics, connections through which the pneumatics are controlled 20 from the control ducts, locking elements for said movable members, respectively, and means under control of the tone ducts for moving the locking elements into holding relation with said movable members.
- 40 9. In a record-controlled musical instrument of the kind set forth, tone connections including a set of levers each of which is provided with a member movable therewith to make the corresponding connection operative or inoperative, and a common operating member for the set of levers, having a plurality of yieldable supports projecting therefrom and engaging the levers, respectively.
- 45 10. In a record-controlled musical instrument of the kind set forth, tone circuits, a set of circuit making and breaking members, a lever carrying each circuit making and breaking member, a common operating member for the set of circuit making and breaking members, and yieldable supports projecting from said operating member and engaging the levers, respectively.
- 50 11. In a record-controlled musical instrument of the kind set forth, tone connections including a set of levers each of which is provided with a member movable therewith to make the corresponding connection operative or inoperative, a common operating member for the set of levers, having a plu- 55 rality of yieldable supports projecting therefrom and engaging the levers, respectively, and retracting spring connected to said levers.
12. In a record-controlled musical instrument of the kind set forth, tone-connections including a set of levers each of which is provided with a member movable therewith to make the corresponding connection operative or inoperative, a common operating member for the set of levers, having a plurality of yieldable supports projecting therefrom and engaging the levers, respectively, 70 levers connected to the ends of the said operating members, a shaft, cams extending 75 from the shaft and engaging the last mentioned levers, and means for turning said shaft.
13. In a record-controlled musical instrument, of the kind set forth, tone-connections including a set of levers each of which is provided with a member movable therewith to make the corresponding connection operative or inoperative, a common operating member for the set of levers, having a plurality of yieldable supports projecting therefrom and engaging the levers, respectively, 80 and operating means for said operating member, including levers connected to the ends thereof, a shaft, cams projecting from 85 the shaft and engaging the last mentioned levers, operating pneumatics and connections between the operating pneumatics and shaft.
14. In a record controlled musical instrument, a plurality of scales of tone-emitting elements, tone-connections, including a set of levers for each scale of tone-emitting elements, said levers having members movable therewith to render the corresponding connections operative or inoperative; operating members common to the respective sets of levers; operating pneumatics; shafts; connections between the operating pneumatics and the shafts; connections between the 90 shafts and the operating members; and means to control the relative pressures to which the operating pneumatics are subjected, to maintain one set of levers normally in position in which the connections 95 to the corresponding tone-emitting elements are established and to hold the other set of levers normally in position in which the connections to the corresponding tone-emitting elements are interrupted.
15. In a record-controlled musical instrument, a plurality of scales of tone emitting elements, tone-connections, including a set of levers for each scale of tone-emitting elements, said levers having members movable 100 therewith to render the corresponding connections operative or inoperative; operating members common to the respective sets of levers; and means for operating said members, including operating pneumatics hav- 105 110 115 120 125 130

ing connections therewith, air connections to said pneumatics, respectively, and a pneumatically-operable valve in each of said connections to control the pneumatic forces to hold one operating pneumatic normally collapsed and the other normally expanded.

16. In a record-controlled musical instrument, a plurality of scales of tone emitting elements, tone-connections, including a set 10 of levers for each scale of tone-emitting elements, said levers having members movable therewith to render the corresponding connections operative or inoperative; operating members common to the respective sets 15 of levers; and means for operating said members, including operating pneumatics having connection therewith, air connections to said pneumatics, respectively, a pneumatically operable secondary valve in each 20 connection, and pneumatically operable valves for controlling the pneumatic forces to hold the first-mentioned valves normally in position to cause one operating pneumatic to be normally collapsed and the other to 25 be normally expanded.

17. A record-controlled musical instrument, a plurality of scales of tone emitting elements, comprising tone-connections having a set of circuit making and breaking 30 members for each scale of tone-emitting elements and record-controlled means for completing the circuits which include said members; a common operating member for each set of circuit making and breaking members; an operating pneumatic for each operating member; air connections to said pneumatics, respectively; a pneumatically operable valve in each of said connections; and record-controlled means to control the 40 pneumatic forces to said valves, to hold one operating pneumatic normally collapsed and the other normally expanded.

18. A record - controlled musical instrument, a plurality of scales of tone emitting 45 elements, comprising tone-connections having a set of circuit making and breaking members for each scale of tone-emitting elements and record-controlled means for completing the circuits which include said members; a common operating member for each set of circuit making and breaking members; an operating pneumatic for each operating member; air connections to said pneumatics respectively, each including a pneumatically 50 operable secondary valve and record-controlled valves respectively having connection

with the secondary valves and controlling the pneumatic forces which act to hold one secondary valve normally in position to maintain one operating pneumatic normally collapsed and the other secondary valve normally in position to maintain the other operating pneumatic normally expanded.

19. A record - controlled musical instrument of the kind set forth having tone connections for a plurality of scales of tone emitting elements, a series of circuit closing members in the tone connections for each scale, pneumatic means for operating the members and common to a plurality thereof, 60 loose connections between the pneumatic means and the members to transmit motion from the former to the latter and pneumatically controlled means for controlling the pressure on said pneumatic means.

20. A record - controlled musical instrument of the kind set forth having tone connections for a plurality of scales of tone emitting elements, a series of circuit closing 70 levers in the tone connections for each scale, pneumatic means for operating the members and common to a plurality thereof, 75 loose connections between the pneumatic means and the levers to transmit motion from the former to the latter and pneumatically controlled means for controlling the pressure on said pneumatic means.

21. A record-controlled musical instrument of the kind set forth having tone connections for a plurality of scales of tone emitting 80 elements, a series of circuit closing members in the tone connections for each scale, pneumatic means for operating the members, 85 loose connections between the pneumatic means and the members to transmit motion from the former to the latter and pneumatically controlled means for controlling the pressure on said pneumatic means.

22. A record - controlled musical instrument of the kind set forth having tone connections for a plurality of scales of tone emitting 90 elements, a series of circuit closing members in the tone connections for each scale, pneumatic means for operating the members, 95 loose connections between the pneumatic means and the levers to transmit motion from the former to the latter and pneumatically controlled means for controlling the pressure on said pneumatic means.

In testimony whereof I affix my signature.

HEINRICH BOCKISCH.
